UNITED STATES PATENT OFFICE.

SAMUEL D. CRUSE, OF LOUISVILLE, KENTUCKY.

WASTE-RECLAIMER.

1,283,094.

Specification of Letters Patent. Patented Oct. 29, 1918.

Application filed July 14, 1917. Serial No. 180,522.

To all whom it may concern:

Be it known that I, SAMUEL D. CRUSE, a citizen of the United States, residing in the city of Louisville, county of Jefferson, and 5 State of Kentucky, have invented certain new and useful Improvements in Waste-Reclaimers, of which the following is a specification.

This invention relates to waste reclaimers 10 adapted to be used in connection with bat forming machines or other fiber manipulating apparatus of a similar nature.

When fiber handling machines, such as bat formers are in service, some material will 15 fall through to the floor, whereas it is difficult of access, it is allowed to accumulate until necessity requires its removal, in the meantime dirt and oil which falls thereon from the machine, renders it unfit for use, 20 until cleaned.

An object of this invention, is to provide a device adapted to be installed under, and in connection with apparatus now in service, which will gather up the fiber as fast as it 25 falls on the floor and return it to the hopper of the machine.

A further object is the provision of a device of the character described which shall be economical in construction, durable in 30 operation and efficient in service.

With the foregoing and other objects in view, the invention consists of the novel construction and arrangement of parts illustrated in the accompanying drawing, which 35 forms a part of this specification, wherein is set forth an embodiment of the invention, but it is to be understood that such changes and modifications may be resorted to as come within the scope of the claims ap- 40 pended hereunto.

Referring now to the drawing, wherein similar reference characters designate like parts in the different views, Figure 1, is a plan view of the device as positioned for 45 service, the relative position of the machine with which it is associated being indicated by dotted lines: Fig. 2, a side elevation of Fig. 1: Fig. 3, a section on line 3—3 of Fig. 1: Fig. 4, a front elevation of the device.

The device is intended to be installed directly on the floor under and along side of a previously erected machine, the feed hopper —1— of which is indicated by dotted lines, while the bottom of the body of the 55 machine is indicated by a dotted line —2— (see Fig. 2). The construction of the de-

vice is as follows: A pair of brackets —4 and 5— are secured to the floor, in spaced relationship, at one side of the machine at the hopper end thereof. On the other side 60 of the machine and in alinement with the first bracket, a third bracket —6— is positioned. A shaft —7— journaled in these brackets carries a screw conveyer —8—, and a bar —9— connects the brackets 4, 5, and 65 6. A plate of sheet metal —10—, secured along one edge to the bar 9 extends downward and forward, following the curvature of the screw conveyer, forming what may be called a trough therefor, and is secured 70 to the floor by suitable means such as nails or screws —11—. An elevator leg —12— erected beside the feed hopper, extends upward from the end of the trough, and is provided at its upper end with a spout 75 —13— which discharges into the hopper. A conveyer belt —14—, within the leg is driven from the shaft 7 by means of a sprocket chain —15—. A shaft —16— journaled in the brackets 4 and 5, is pro- 80 vided on its outer end with a sprocket wheel —17—, which provides means whereby power may be supplied from a suitable source, usually a moving part of the machine. A pinion —18— on the shaft 16 85 meshes with a corresponding pinion on the shaft 7, whereby power is transmitted to the last named shaft. A shaft —20— is journaled in the brackets 4 and 5 and in a bracket —21— positioned a spaced distance 90 from the bracket 5. A shaft —22— is journaled in the bracket 6 and a bracket —23— spaced inward therefrom. The two shafts 20 and 22 are in axial alinement and are driven uniformly and continuously from 95 the shaft 7 by means of sprocket chains —24—. Lugs —25— integral with and ex- 100 tended forward from the brackets 21 and 23 are adapted for the rigid attachment thereto of the rear ends of parallel longi- tudinal bars —26—. The forward ends of 105 these bars are carried by brackets —27—, which are provided with slots —28— through which the bars extend and in which they are secured by suitable means such as set screws —29—. This arrangement is used in order to adapt the device for in- 110 stallation in connection with machines of different lengths. The device is supplied with bars 26 of sufficient length to permit it to be used with the largest bat forming machine. If the device is to be installed in

connection with a smaller machine, the brackets 27, are slid along the bars until they are in the proper position relative to the machine, secured on the bars by means 5 of set screws, and then fastened to the floor. Pins —30— project forward from the bracket 27 and carry sleeves —31— which may be adjusted in position therealong by means of set screws —32—. These sleeves 10 carry bearings —23— which are formed integral therewith, in which a shaft —34— is journaled. Sprocket wheels —35— are mounted on this shaft near each end thereof. Sprocket wheels —36— are mounted re- 15 spectively on the inner ends of the shafts 20 and 22, in alinement with the sprocket wheels 35 on the shaft 34. A pair of drag chains —37— are trained about the sprocket wheels 35 and 36, and drag bars —39— are 20 secured to said chains at spaced intervals therealong. In operation the travel of the drag chains is such that the drag bars move, in proximity to the floor, from the front to the rear, gathering fiber, that falls from 25 the machine and dragging it to the screw conveyer which delivers it to the conveyer belt which carries it up the elevator leg and deposits it in the spout down which it slides into the hopper of the machine. As 30 the fiber is drawn up along the bottom of the elevator leg it passes over a reticulated position —40— through which any dirt or dust carried along will fall.

It is to be observed that the waste material 35 is delivered to the screw conveyer along substantially its entire length, and that there is no shaft in the way to obstruct free delivery thereto, as the sprocket wheels 36 are on the inner ends of the shafts 20 and 22.

40 Having thus described my invention so that any one skilled in the art pertaining thereto may make and use the same I claim:

1. In a waste reclaimer, a main shaft, a screw conveyer carried thereby, a pair of 45 intermediate short shafts mounted co-axially, a spaced distance from and parallel with the main shaft near the respective ends thereof, and adapted to be driven thereby, a sprocket on the inner end of each of said 50 short shafts, a pair of parallel bars, means

for supporting the inner ends of said bars in proximity to the short shafts, brackets provided with slots through which the outer ends of the bars pass, a pin extended forward from each of said brackets, a sleeve 55 adjustably positioned on said pin, bearings carried by said sleeves, a shaft rotatably mounted in said bearings, sprockets positioned on said shaft, said sprockets being in alinement with the sprockets on the intermediate shafts, chains trained about the sprocket wheels, and bars attached to the chains at spaced intervals therealong.

2. In a waste reclaimer, a pair of brackets in spaced relationship, a third bracket distant from said pair, a main shaft rotatably mounted in said brackets, a screw conveyer carried by said shaft, a pair of intermediate short shafts co-axially mounted parallel with the main shaft, the outer ends of said 70 intermediate shafts journaled respectively in said pair of brackets and in said distant bracket, brackets in which the inner ends of the intermediate shafts are journaled, said shafts adapted to be driven from the 75 main shaft, bars secured to and extending respectively from the last named brackets in parallel relationship, another pair of brackets provided with slots through which said bars extend, means whereby the bars 80 may be secured in said slots, pins extended forward from the last named brackets, sleeves positioned on said pins and adapted to be adjusted therealong, bearings carried by said sleeves, a shaft journaled in said 85 bearings, sprockets secured respectively on said shaft and on the intermediate shafts, chains trained about said sprocket wheels and bars attached to said chains at spaced intervals therealong.

3. A pair of brackets disposed in spaced relationship, a rail rigidly attached to and extending from each bracket, a second pair of brackets provided with slots in which said rails are adjustably secured, a stub shaft extended from each of said last mentioned brackets, sleeves adjustably positioned on said shafts and co-axially disposed journal bearings carried by said sleeves.

SAMUEL D. CRUSE.
